C. H. HODGES.
AUTOMATIC VALVE REGULATOR.
APPLICATION FILED JUNE 8, 1917.

1,341,319.

Patented May 25, 1920.

UNITED STATES PATENT OFFICE.

CHARLES H. HODGES, OF NEW YORK, N. Y., ASSIGNOR TO CONSOLIDATED GAS COMPANY OF NEW YORK, A CORPORATION OF NEW YORK.

AUTOMATIC VALVE-REGULATOR.

1,341,319.

Specification of Letters Patent.

Patented May 25, 1920.

Application filed June 8, 1917. Serial No. 173,464.

To all whom it may concern:

Be it known that I, CHARLES H. HODGES, a citizen of the United States, residing at New York city, N. Y., have invented certain new and useful Improvements in Automatic Valve-Regulators, of which the following is a clear, full, and exact description.

My invention relates to means for automatically regulating the rate of flow of fluid through a conduit by means of a valve caused to open or close at a predetermined speed.

While my invention is applicable to a wide variety of uses, a particular application thereof is in connection with the carbureter blast valves of water gas generating plants. As is well known, in the manufacture of water gas the generator is filled with fuel, through which a blast of air is forced after the fuel is lighted. The gases passing off from the fuel are conducted to a compartment in which they are caused to heat a mass of loosely piled brick or the like. After a short time, the air blast through the fuel is shut off and steam is forced therethrough; this steam reacts on the glowing fuel to form water gas. This water gas, however, has very low illuminating value; to repair this defect, it also is passed through the heated compartment into which oil is admitted, and this compartment therefore becomes a carbureter, since oil, when exposed to the high temperature of the compartment, breaks up into various hydro-carbons which, mixing with the water gas, add greatly to its illuminating value.

In order that this carburizing may be economically and effectively conducted, it is essential that the hot gases formed by the preliminary air blast through the generator should be completely burned and yet should not be diluted by excess air. To accomplish this, it is usual, during the preliminary stage of heating the carbureter, to introduce a second air blast between the generator and the carbureter. This is known as the carbureter blast, and the valve by which it is controlled is called the carbureter blast valve. Economical operation requires that the opening of this valve should be gradual to admit a constantly increasing supply of air to correspond with the gradual increase that takes place in the amount of CO or "blue gas" that passes over from the gener-

ator, and to reduce the back pressure against the generator blast.

At the present time it is the practice for the workman in charge to regulate the carbureter blast by manually adjusting the carbureter blast valve from time to time. Since these adjustments are necessarily frequent, the workman frequently becomes careless and either neglects to open the valve at the proper time to a sufficient extent, thus causing an incomplete combustion of the gases in the compartment, or else opens the valve too quickly, thus diluting the gases and cooling off the compartment. Analogous conditions exist in other industries and require that a valve be opened or closed at a predetermined rate.

It is therefore an object of my invention to provide, in connection with a valve, automatic means for opening or closing the valve, which means may be set to move the valve at a desired predetermined speed. A further object is to provide automatic valve controlling means which may be readily connected to and disconnected from the valve, and which, therefore, permits of a ready control of the extent of movement of the valve by the automatic controlling means.

Other objects and advantages of my invention will appear from the following detailed description taken in connection with the accompanying drawing, in which—

Figure 1 is an elevation, partly in section, of my automatic valve regulator mounted on a valve; and

Fig. 2 is a cross section taken on line 2—2 of Fig. 1.

By way of illustration I have shown my automatic valve controlling means in connection with a vertically movable gate valve, which is provided with manually operated means for moving the valve when the automatic controlling means is disconnected therefrom or is inoperative. It is however, to be understood that my invention is not limited to such an arrangement.

In the arrangement shown, the pipe or conduit 1 is fitted with a valve casing 2 having a gate valve 4 vertically movable therein and provided with a vertical valve stem 6 in the form of a rack-bar. Meshing with this rack-bar is a pinion 8 carried on a horizontal shaft 10 journaled in the upper portion 12 of the valve casing and having at 110

one end a hand-wheel 14. Vertically aligned with the valve casing 2 is the cylinder 16 supported on the upper portion 12 of the valve casing 2 by means of the legs 18. The 5 piston 20 is vertically movable in the cylinder 16 and carries a depending piston rod 22 sliding through the lower head 24 of the cylinder. To the lower end of the rod 22 is detachably connected the yoke 26, adapted 10 to receive the valve stem 6 through the opening 28 in its lower end. A set screw or dog 29 serves to quickly secure the valve stem in the yoke.

Opening into the lower end of the cylinder 16 are the pipes 30 and 32 provided with the quick opening valves 34 and 36 respectively. These valves are provided with the handles 40 and 42, which are connected by the link 44 in such manner that when one 15 valve is opened, the other is simultaneously closed. In one of the pipes is fitted an adjustable throttling valve 46, the stem of this valve being provided with a handle 48 and a pointer 50. The pointer coöperates with 20 the semi-circular scale 52 to indicate the extent of opening of the valve.

The upper end of the cylinder is provided with a pipe 54 for carrying off such fluid as may leak past the piston.

30 Either of the pipes 30 or 32 may be used as the inlet pipe, the other being the exhaust pipe. When 32 is the inlet pipe in the arrangement, the device is operated by admitting fluid to the underside of the piston 20 by opening the valve 36 and simultaneously closing the valve 34, the throttle valve 46 being set to permit such a rate of flow through the pipe 32 as will raise the piston 20 at the desired speed. When the 35 valve 4 has been opened the desired distance, the valve stem 6 may be quickly disconnected from the yoke 26 by disengaging the dog 29. The piston is then allowed to descend by closing the valve 36 in the inlet pipe and opening the valve 34 in the exhaust pipe.

It may, however, be desired to regulate the speed at which the valve closes. In such a case, 32 would be used as the exhaust pipe, 50 the piston having first been raised by admitting fluid through the pipe 30. The rate of flow out of the cylinder and the consequent rate of descent of the piston and the attached valve under the influence of the 55 force of gravity is, in such case, determined by the position to which the throttle valve 46 is adjusted.

While I have shown and described one of the preferred embodiments of my invention, 60 it is understood that my invention is not

limited to such embodiment. The principle thereof may be applied through valves and cylinders in different relative positions and may be utilized by means of different mechanism for controlling the rate of change in 65 the amount of fluid in said cylinder and the method of communicating the movement of the piston, or other fluid controlled member, to the valve.

What I claim as new is—

1. In combination with a valve, fluid controlled means arranged to operate at a predetermined speed, and means for connecting said fluid controlled means to said valve, provided with means for quickly attaching 75 and detaching the connecting members of said connecting means during the operation of the valve without rotating said members.

2. In combination with a valve having a vertical valve stem, a vertical cylinder above 80 said valve, a piston in said cylinder, a piston rod depending from said piston and extending through the lower head of said cylinder, a yoke suspended from the lower end of said piston, quick operable means for detachably connecting the lower end of said yoke to said valve stem, means for admitting fluid to or discharging it from the underside of said piston at a predetermined rate of flow to cause the same to be raised or 85 lowered gradually.

3. In combination with a valve, fluid controlled means adapted to operate said valve at a predetermined speed and comprising a cylinder provided with a piston, two supply 95 pipes arranged to connect with one end of said chamber at the side of one face of said piston, each pipe having a control valve, both of said control valves being controlled in common, one to open and the other to 100 close, means for connecting said fluid controlled means with the first said valve, and means for controlling, at will, the rate of flow of fluid through said control valves.

4. In combination with a valve having a 105 valve-stem in the form of a rack, a fluid operated device, means for detachably connecting said stem with said fluid operated device to operate said valve, and a manually operable pinion in mesh with the teeth of 110 said rack, adapted for the manual operation of said valve when said fluid operated device and valve are detached.

Signed at New York city, N. Y., this 7th day of June, 1917.

CHARLES H. HODGES.
